UNITED STATES PATENT OFFICE.

ROBERT F. CARTY AND WILLIAM A. DOWNES, OF DETROIT, MICHIGAN.

TOY PISTOL.

SPECIFICATION forming part of Letters Patent No. 545,345, dated August 27, 1895.

Application filed June 15, 1895. Serial No. 552,963. (No model.)

To all whom it may concern:

Be it known that we, ROBERT F. CARTY, a citizen of Canada, and WILLIAM A. DOWNES, a citizen of the United States, residing at 5 Detroit, county of Wayne, State of Michigan, have invented a certain new and useful Improvement in Toy Pistols; and we declare the following to be a full, clear, and exact description of the invention, such as will enable others skilled in the art to which it pertains to make and use the same, reference being had to the accompanying drawings, which form a part of this specification.

This invention relates to toy pistols, and has 15 for its object an improvement in that class of pistols in which the detonating paper wafer-shaped cap is exploded, the especial object being to provide a magazine into which a number of the paper caps can be loaded preparatory to exploding them and a pistol into 20 which the magazine can be inserted and by which the caps can be exploded successively until the magazine is empty.

In the drawings, Figure 1 is a sectional elevation. Fig. 2 shows the magazine in perspective. Fig. 3 shows the pistol in rear elevation.

A indicates the barrel, and B the grip. The barrel projects both to the front and to the 30 rear of the grip.

C indicates the trigger-case and is a prolongation of the grip under the barrel and on the forward side of the grip.

The trigger is indicated at D, and is a lever 35 hung on a pin d, having the outward projection d' for the finger. The upwardly-extended projection d² engages with a rack on the under side of the magazine, and a forward engaging-lug d³ engages with the spring c, which 40 is held on a pin c' and a notch c² in the casting. Above the trigger is a hammer H, which turns on pins h and is pulled backward and a face h² raised, preparatory to making its stroke against the cap, either by the ear h' or 45 by the rack-teeth on the magazine M. A spring h³ is put under tension when the face of the hammer is raised, and when the hammer is released throws it violently back to explode the cap.

On each side of the pistol-barrel A and its 50 rear extension a and within the barrel is a groove which serves to guide the magazine as it is pushed along through the barrel by the actuating impulses of the trigger D. The hole through the trigger D is oval, and the 55 pin d is round, thus permitting a little play of the trigger on its pin and enabling the upper end of the trigger to pass back along the teeth of the lower rack and to rise and engage behind the teeth successively. The spring c holds 60 the trigger with its upper end in contact with the rack. The magazine M is in the form of a plate or bar of a width suitable to engage in the grooves g g, and to pass freely through the barrel from rear to front. On the under 65 side of the magazine are a number of ratchet-teeth g', adapted to engage the projection d² of the trigger, and on the upper side or along one edge of the magazine are teeth m. On the upper side also there are a number of 70 cavities n, which are used as receptacles for the common detonating-cap, these caps consisting of a thin wafer-shaped particle of detonating compound held between disks of thin paper. The upper side of the magazine 75 M is provided with receptacles or cavities into which the caps are placed, and it is also provided with a number of teeth m, which engage successively, as the magazine travels forward, with the prong p of the hammer H, and 80 raise the hammer until the tooth has passed under the prong p, when the hammer is violently thrown down by the spring h³. When the magazine has passed through under the hammer it is pulled out from the barrel and 85 reloaded again and inserted at the other end to be used again.

A special feature of this pistol is that the ordinary cap found on sale in stores and described above can be used in this magazine, 90 and, further, the explosion takes place entirely within the barrel, thus obviating any danger from flying particles of the detonating compound.

What we claim is—

1. In a toy pistol, the combination of a barrel, a magazine provided with a rack on its under side, and a rack on its upper side, a

trigger adapted to engage the lower rack and push the magazine forward, a hammer adapted to be raised by the upper rack, and a spring adapted to drive the hammer downward, substantially as described.

2. In a toy pistol the combination of a barrel, a magazine adapted to be advanced through the barrel, and provided with receptacles for detonating caps, a hammer adapted to be alternately raised by the magazine and

to strike against the caps carried thereby, substantially as described.

In testimony whereof we sign this specification in the presence of two witnesses.

ROBERT F. CARTY.
WILLIAM A. DOWNES.
